UNITED STATES PATENT OFFICE.

JOHN BORGNA FLAUTT, OF SPARTA, WISCONSIN.

PAINT-BRUSH ATTACHMENT.

SPECIFICATION forming part of Letters Patent No. 398,244, dated February 19, 1889.

Application filed May 9, 1888. Serial No. 273,265. (No model.)

To all whom it may concern:

Be it known that I, JOHN BORGNA FLAUTT, a citizen of the United States, residing at Sparta, in the county of Monroe and State of Wisconsin, have invented certain new and useful Improvements in Paint-Brush Attachments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to a combined drip-guard and bridle for brushes, and has for its object the construction of a device that can be readily adjusted to any brush to prevent a too great spread of the brush and to prevent drippings on the floor.

20 The improvement consists of an annular-shaped vessel having the sides of the inner wall parallel and the sides of the outer wall flaring, and having the upper edge of the inner wall turned in to form a flange, and having the upper edge of the outer wall provided with a flexible rim which extends over the mouth of the drip-guard and prevents the spilling of the drippings.

25 The improvement further consists of the details of construction which hereinafter will be more fully described and claimed, and shown in the annexed drawings, in which—

30 Figure 1 is a side view of a brush having my improvement applied; and Fig. 2, a side view of the brush, showing the attachment in section and adjusted on the brush.

35 The device is composed of the inner wall, A, having parallel sides, the outer flaring wall, B, united to the inner wall at the end C, and the flexible rim D, which is attached at its outer edge to the upper end of the wall B by

having the edge of the said wall B bent over it, and has its inner edge extending over the mouth of the guard in a horizontal direction 45 close to the end of the wall A, but leaving sufficient space between the edge of the rim D and the end of the wall A for the entrance of drippings into the guard. The rim prevents the accumulated drippings from splashing out 50 when handling the brush, and it can be turned back about the wall B when emptying or cleaning the guard, as shown by dotted lines in Fig. 2. The upper end of the wall A is turned in to form the flange a, which compresses the brush and catches the drippings 55 and directs them into the guard.

The device can be adjusted on the brush to any desired position, and may be of any required form in cross-section to adapt it to the 60 shape of the brush to which it is to be applied.

Having thus described my invention, what I claim, and desire to secure by Letters Patent, is—

1. The combination, with the combined 65 drip-guard and bridle, of the flexible rim secured to the upper end of the outer wall and having its inner edge extending over the mouth of the guard, substantially as and for the purpose specified.

2. The hereinbefore-specified combined drip-guard and bridle, composed of the wall A, having parallel sides and an inner flange, a, the flaring wall B, united at its lower end to the wall A, and the flexible rim D, having its outer edge secured to the wall B, having the end of the wall bent over it, substantially as set forth. 75

In testimony whereof I affix my signature in presence of two witnesses.

JOHN BORGNA FLAUTT.
